UNITED STATES PATENT OFFICE.

WILLIAM BUTTLER, OF REDKEY, INDIANA.

DESIGN FOR A LAMP-CHIMNEY.

SPECIFICATION forming part of Design No. 24,471, dated July 16, 1895.

Application filed May 31, 1895. Serial No. 551,329. Term of patent 14 years.

To all whom it may concern:

Be it known that I, WILLIAM BUTTLER, of Redkey, in the county of Jay and State of Indiana, have invented a new and original Design for Lamp-Chimneys, of which the following is a full, clear, and exact description, reference being had to the accompanying drawing, forming part of this specification, which shows in side elevation a lamp-chimney embodying my design.

The essential feature of the design consists in a lamp-chimney having, substantially as herein shown and described, a surface pattern comprising parallel bands extending circumferentially around the chimney and between which is a plain band having thereon a series

of substantially-circular figures set at substantially-equal distances from each other.

In the drawing, 2 represents the chimney; 3 4, the parallel bands; 5, the intermediate plain band, and 6 6 the series of substantially-circular figures.

I claim—

The design for lamp-chimneys substantially as herein shown and described. 25

In testimony whereof I have hereunto set my hand.

WILLIAM BUTTLER.
